UNITED STATES PATENT OFFICE.

GEORGE L. SMITH, OF NEWARK, NEW JERSEY.

LOOP FOR BRIDLES.

SPECIFICATION forming part of Letters Patent No. 315,672, dated April 14, 1885.

Application filed January 26, 1885. (No model.)

To all whom it may concern:

Be it known that I, GEORGE L. SMITH, of Newark, in the county of Essex and State of New Jersey, have invented certain new and 5 useful Improvements in Loops for Bridles, &c., of which the following is a specification.

My invention relates to overcheck-guides for bridles; and it consists in a loop or guide composed of two uprights provided with feet 10 for attachment to the bridle, connected by a cross-bar provided with a loose sleeve or roller, and having upwardly-turned ends to prevent the accidental displacement of the rein.

In the drawings annexed, Figure 1 is a perspective view of my improved guide, and Fig. 15 2 a face view showing the sleeve or roller in section.

The purpose of my invention is to produce a guide into and from which the rein may be 20 readily inserted and removed, and which shall permit the rein to slide or move freely and without chafing.

Prior to my invention guides have been formed with inwardly-turned ends separated 25 sufficiently to permit the rein to be inserted edgewise between them, yet not enough to permit the accidental escape of the rein, and closed loops have been provided with a closed loose sleeve or roller. These features, separately considered, are not therefore claimed by 30 me.

My improved guide is shown in the drawings, in which A A indicate two uprights having feet *a* for attachment to the bridle by means of rivets or other fastenings, and the 35 upper ends, *b*, of which are bent over into a substantially horizontal position with a narrow space between them, as shown in Fig. 2.

B indicates a cross-bar connecting the uprights A A, and encircled by a sleeve or roller, 40 C, which is free to rotate thereon. The height of the uprights A and the position of cross-bar B are such that the sleeve or roller may not touch the crown-piece of the bridle, to which the guide is applied, (two being employed ordinarily,) and that sufficient space 45 shall be left between the roller and the bent arms or ends *b* to permit the rein or strap to move freely therein.

The construction produces a very cheap and 50 efficient guide, and one which will in no way chafe or injure the rein.

Having thus described my invention, what I claim is—

The herein-described guide for check-reins, 55 &c., consisting of uprights A A, having ends *b* bent laterally toward each other, connecting-bar B, and loose sleeve or roller C.

GEORGE L. SMITH.
